COLLETS AND OTHER WORKHOLDERS

Cecil John Linzell, Witney, England, assignor to Crawford Collets Limited, Witney, England, a company of Great Britain

Filed Jan. 11, 1960, Ser. No. 1,668

Claims priority, application Great Britain July 10, 1959

8 Claims. (Cl. 279—46)

This invention relates to collets and other work-holders, and in particular to collets provided with detachable work-engaging pads.

One object of the present invention is to provide a work-holder such as a collet having one or more work-engaging pads each of which is readily releasable from the work-holder, the means for locking the pad to the jaw and for releasing the pad from the jaw being simple to manufacture and to operate and involving the minimum of moving parts.

The invention provides a work-holder comprising in combination a jaw, a work-engaging pad; means for progressively urging said pad into engagement with said jaw, said means comprising a spring, a member supported by said jaw for movement longitudinally thereof under the force of said spring, said member having a surface facing said jaw and inclined to the direction of movement of the member, which surface is adapted to engage against a co-operating surface on said pad, said co-operating surface facing away from said jaw and lying substantially parallel to said surface on said member.

The invention further provides a work-holder comprising in combination a jaw, a work-engaging pad, means for locating said pad on said jaw, means for releasably locking said pad to said jaw, said means comprising a plunger slidable in a re-entrant keyway extending parallel to the length of the jaw formed in one member of the pair of members consisting of said pad and said jaw, mutually engaging members comprising a dovetail member and means defining a dovetail slot adapted to receive said dovetail member, one of said engaging members forming part of said plunger and the other of said engaging members forming part of the other member of said pair of members, the mutually engaging surfaces of said dovetail member and slot lying at an inclination to the direction of movement of the plunger.

One embodiment of the invention is shown, by way of example only, in the accompanying drawing in which:

Figure 1 is a section through a collet;

Figure 2 is a plan view of the collet of Figure 1;

Figure 3 is a rear view of a work-engaging pad with a plunger and spring attached thereto;

Figure 4 is a perspective view of the work-engaging pad;

Figure 5 is a perspective view of the plunger and spring;

Figures 6 and 7 are respectively a plan view from below and a side view of the plunger;

Figures 8 and 9 are sections through part of the collet showing the positions of the plunger in which the work-engaging pad is respectively locked and released;

Figure 10 is a side elevation of the plunger in engagement with the work-engaging pad, showing in chain dotted line, the released position of the plunger;

Figure 11 is an elevation of the work-engaging pad seen from the rear.

Figures 12 and 13 are views from below of the work-engaging pad with the plunger respectively in position and removed.

2

According to the embodiment of the invention shown in the drawing, the collect 10 is divided by longitudinal slits 10a to provide a number of similar jaws 10b, for example three, and on the inside of each jaw a work-engaging pad 11 is supported. As the three work-engaging pads and their means of support will usually be identical, only one will be described.

Around the outer face of the pad, a shoulder 11a is formed the sides of the shoulder lying in planes normal to the longitudinal axis of the collet. A corresponding groove 10c is formed in the inner face of the collet jaw, against which face the pad abuts, to receive the shoulder and thereby prevent movement of the pad in a direction parallel to the longitudinal axis of the collet.

15 The pad is held in position on the jaw by means which permit it to be readily released when desired. These means comprise a plunger 12 which fits slidingly in a chamber 10d (Figures 1 and 8) formed longitudinally in the jaw in a mid-position and opening along its length 20 through the concave surface of the jaw in the manner of a re-entrant slot. This is best seen in Figure 1 where the plunger is in position but the pad has been removed.

The plunger 12, which over a short upper portion 12a is of circular cross-section, is part cylindrical below this 25 upper portion and has a substantially flat face 12b parallel to the axis of the plunger over a mid-portion; over a lower portion it is formed with a dovetail-shaped key 12c, the outer surface 12d of the dovetail, that is the surface between the inclined sides thereof, lying at a small acute 30 angle, for example 7°, to the flat face of the mid-portion of the plunger, the faces 12e of the plunger on either side of the base of the dovetail being parallel to the outer surface 12d of the dovetail.

35 The shoulder 11a on the pad in the vicinity of the plunger is cut away to provide a dovetail keyway 11b matching the dovetail key 12c of the plunger in shape and inclination, the face 11c of the shoulder which lies adjacent the base of the groove 10c in the jaw being chamfered on either side of the dovetail keyway to match the inclined 40 faces 12e of the plunger on either side of the dovetail key.

It will be evident therefore that if the pad is fitted in place when the plunger is in a low position in its chamber, on raising the plunger the dovetail key will enter 45 the dovetail keyway in the pad and the inclination of the engaging surfaces will pull the pad into progressively tighter contact with the jaw.

The movement of the plunger is manually controlled 50 against the force of a spring 13 which at its upper end fits into a cupped recess 12g in the base of the plunger and at its lower end engages the base of the chamber.

Since the upper end of the plunger is fully circular, an adjacent part of the pad 11 is cut away at 11d to allow free 55 movement of the plunger upwards and downwards, and the length of the cut away portion determines the lower limit of movement of the plunger.

The upward movement of the plunger is limited by a stop in the form of a screw 14 which is screwed into the end face of the jaw until the head lies flush with the face of the jaw, but protrudes laterally into the chamber and engages in a short arcuate slot 12h in the side of the plunger. The plunger may of course be removed by first removing this screw. The screw head also serves to prevent rotation of the plunger within the chamber.

In operation of this device, on depressing the plunger 12 against the force of the spring 13, the dovetail key 12c of the plunger is slid out of the dovetail keyway of the pad 11b, and the pad is accordingly released. To replace the pad the plunger is depressed, the pad is fitted 70 into position and the plunger is released whereupon it rises under the force of the spring to bring the dovetail key into engagement with the dovetail keyway of the

pad and, by the inclination of the engaging surfaces, lock the pad tightly to the jaw. It will be appreciated that by reason of the spring-urging of the plunger into the locking position, the device cannot easily be mishandled as for example may be a device employing screw-threaded locking arrangements which may be damaged through overtightening or alternatively work loose through undertightening. It will also be appreciated that by means of this form of locking and release arrangement, a very rapid change of the work-engaging pads may be effected.

Whilst most of the parts described above may be produced by conventional machine-shop methods, it may be preferable to form the plunger by a sintering method.

In a modification of the above embodiment the dovetail key may be provided on the pad, instead of on the plunger, in which case the dovetail keyway will be provided in the plunger.

The above embodiments may also be modified by arranging for the plunger to be raised or lowered on a screw-threaded rod which is rotatable by a key or screw-driver fitted into a head on the rod located in the end face of the jaw.

According to a further modification, the pad may engage with the jaw through a shoulder provided on the jaw to fit into a corresponding recess in the pad.

It will be evident that whilst a dovetail key and keyway have been described above for providing the wedge action by which the pads are held tightly to the jaws, alternative devices providing a similar wedge effect may be designed within the scope of the invention.

I claim:

1. A work-holder comprising in combination a jaw, a work-engaging pad, means for progressively urging said pad into engagement with said jaw, said means comprising a spring, a member supported by said jaw for movement longitudinally thereof under the force of said spring, said member having a surface facing said jaw and inclined to the direction of movement of the member, which surface is adapted to engage against a co-operating surface on said pad, said co-operating surface facing away from said jaw and lying substantially parallel to said surface on said member.

2. A work-holder comprising in combination a jaw, a work-engaging pad, means for locking said work-engaging pad on said jaw, said means comprising a wedge member movable longitudinally of the work-holder to progressively urge said pad into abutment with said jaw.

3. A work-holder comprising in combination a jaw, a work-engaging pad, means for locating said pad on said jaw, means for releasably locking said pad to said jaw, said means comprising a plunger slidable in a re-entrant keyway in one of the pair of members formed by said pad and said jaw, a shoulder formed on said plunger, a shoulder formed on the other member of said pair, one of said shoulders having a surface elongated at an inclination to the direction of movement of the plunger and facing towards the member on which said shoulder is formed, the other shoulder being adapted to engage slidably against said surface and spring means for urging said shoulders into progressively tighter mutual engagement to lock said pad to said jaw, said plunger being movable against the force of said spring means to release said pad from said jaw.

4. A work-holder comprising in combination a jaw, a work-engaging pad, said pad forming with said jaw a pair of interengaging members, at least one projection from one of said interengaging members abutting against a co-operating recess in the other of said members to prevent movement of the pad in at least one direction along the jaw, and means movable alternatively to release said pad from said jaw and to progressively urge

said pad into engagement with said jaw, said means comprising a plunger slidable in a re-entrant keyway extending longitudinally within said jaw, a dovetail projection on said plunger, said pad having a dovetail recess adapted to receive said dovetail projection, those surfaces of said dovetail projection which abut co-operating surfaces of the recess being inclined to the direction of movement of the plunger and a spring adapted to urge said plunger in a direction in which the dovetail projection enters said recess and progressively presses the pad towards the jaw and in which said projection is pressed against a face of said co-operating recess.

5. A work-holder comprising in combination a jaw, a work-engaging pad, said pad forming with said jaw a pair of interengaging members, at least one projection from one of said interengaging members adapted to engage against a face of a recess in the other of said members to prevent movement of the pad in at least one direction along the jaw, movable locking means slidably mounted on one of said interengaging members, the other of said interengaging members having fixed locking means, a spring adapted to urge said fixed and movable locking means into mutual engagement to lock said pad to said jaw.

25 6. A collet having a plurality of longitudinal slots defining a plurality of collet jaws, a plurality of work engaging pads, each pad forming with a jaw a pair of interengaging members, at least one shoulder projecting from one of said members adapted to engage in a corresponding recess in the other of said members to prevent movement of the pad in at least one direction along the jaw, said jaw having a re-entrant slot in a face thereof of adjacent the pad, a plunger slidably mounted in said slot, a spring urging said plunger towards the outer end of said jaw, a dovetail key formed on said plunger, a dovetail keyway formed in said pad to receive said dovetail key, the interengaging surface of said key and keyway being inclined to the direction of movement of the plunger to cause the plunger when moving under the force of the spring to pull said pad into progressively tighter engagement with the jaw.

30 7. A collet comprising a plurality of spring-loaded plungers and a plurality of work-engaging pads, each of said pads being interlocked with a respective one of said plungers in a predetermined position of said pad into which the pad is urged by its spring loading, each pad being released from the collet by movement of its interlocking plunger away from said predetermined position.

35 8. A collet comprising a plurality of work-engaging pads, a plurality of plungers, said plungers being equal in number to said pads, said collet having an axial bore which is recessed at spaced intervals to accommodate said plungers, a plurality of resilient means, each plunger being engaged by one of said resilient means and normally being urged thereby into a predetermined position relative to said bore, each pad having a portion thereof interlocking with a portion of a respective plunger, interengaging surfaces of said pad portion and said plunger portion being inclined at an angle to the axis of said axial collet bore whereby movement of said plunger into said predetermined position draws said pad towards said plunger.
